DESIGN FOR A REVERSIBLE FRONT UNIFORM DRESS

Amy B. Dickey, Adaza, Iowa

Application March 26, 1937, Serial No. 68,415

Term of patent 7 years

To all whom it may concern:

Be it known that I, Amy B. Dickey, a citizen of the United States, residing in Adaza, Greene County, Iowa, have invented a new, original, and ornamental Design for a Reversible Front Uniform Dress, of which the following is a specification, reference being had to the accompanying drawing, forming a part thereof.

Fig. 1 is a front view of the dress with the front buttoned to the left.

Fig. 2 is a front view of the dress with the front buttoned to the right.

The back of the dress is conventional in its appearance.

I claim:

The ornamental design for a reversible front uniform dress, substantially as shown and described.

AMY B. DICKEY.
